COMBINED THROTTLE AND GOVERNOR DEVICE

Addison C. Hoof, Hinsdale, Ill.

Application November 8, 1938, Serial No. 239,514

6 Claims. (Cl. 137—152)

My invention relates to improvements in a combined throttle and governor device.

My invention relates more particularly to devices of the character described which include the carburetor throttle valve and a governor valve of the type adapted to be actuated by the suction in the intake manifold of internal combustion engines.

Wherever governors are used with carburetors today in governing the speed of the internal combustion engine upon which the same are mounted, one of the principal objections to the use thereof is the fact that "cheating" may be accomplished by an operator who has learned how to "cheat". As is well known in the art, when the governor valve is in control of the flow of gases to the internal combustion engine, the throttle valve is usually wide open and the vacuum or suction is transferred from a point adjacent the throttle valve, and where a governor is used in connection with the same, that the vacuum is transferred to a point adjacent the governor valve under all conditions where the governor valve is in a more nearly closed position than the throttle valve. However, where a throttle valve and a governor valve are used, and particularly where the load is comparatively light, the governor valve will be moved to its speed limiting closed position and the throttle valve may be manipulated manually to approach the same degree of closing as the governor valve. Where this is done in a careful manner by a driver and the throttle valve is gradually manipulated to the exact point where the throttle valve is approximately at a position where the opening is equivalent to the governed speed of the vehicle, the condition of suction or vacuum changes, moving past the governor valve to a point adjacent the throttle valve. This causes the resistance means acting on the governor valve to cause the same to move to an open position and when the throttle valve is gradually moved to a more open position, the vehicle can of course be operated at greater than the governed speed, resulting in what is termed "cheating", or in other words, over-speeding the set speed of the governor.

As a matter of illustration, if a predetermined speed of 40 M. P. H. is the setting of the governor, and opening of the valve is approximately 10°, with one-eighth of a full load, to permit this speed the spring resistance means for resisting the closure of the governor valve permits a 10° opening. If the throttle valve is now moved to the same opening or a trifle smaller opening than the governor valve, it creates a partial vacuum above

the governor valve equivalent to approximately $\frac{2}{3}$ the vacuum below the governor valve.

This condition has been recognized for many years in the manufacture of vacuum and velocity type governors, and by some manufacturers a partial correction has been made by inserting a dashpot or piston and plunger in a separate opening to the atmosphere and attached to the valve of the governor. This piston is placed between the governor valve and the throttle valve so that when a partial vacuum is created at this point the atmosphere pressure creates an additional means of overcoming the spring resistance means and closes the valve to the predetermined set speed of 40 M. P. H., thereby defeating the attempt to overspeed on the part of the operator or manipulator of the throttle valve.

The present invention relates to an improvement in the combination of a governor and throttle valve whereby "cheating" is not possible.

The principal object of the present invention is to provide an improved mechanism which includes a co-operating means between the throttle valve and the governor valve capable of eliminating "cheating".

A further object of the present invention is to provide an improved unit capable of being positioned between the throttle and the intake manifold of an automotive engine adapted to provide manual control of the fuel feed and means associated therewith whereby automatic means will be in control at all times when the manual means are not in control.

A further object of the present invention is to provide a device of the type described whereby synchronous movement of the throttle and governor valves is obtained for the purpose of eliminating "cheating" and preventing "hunting" or "surging" under part throttle.

A further object of the invention is to provide an improved construction including a throttle valve and a governor valve whereby the governor valve is not capable of being opened more than the throttle valve.

Other objects and advantages will be more apparent from the following description wherein reference is had to the accompanying three sheets of drawings, upon which

Fig. 1 is a front elevational view of my improved unit disposed between the carburetor and the intake manifold of an engine, with a cover of the mechanism chamber in section to more clearly show the parts therein;

Fig. 2 is a plan view of my improved unit with

a portion of the housing broken into section to more clearly show other parts;

Fig. 3 is a front elevational view similar to Fig. 1 with both the governor valve and the 5 throttle valve shown in a closed position;

Fig. 4 is a vertical sectional view of the same taken generally on the lines 4-4 of Fig. 3;

Fig. 5 is a vertical sectional view through the housing and conduit taken generally on the lines 10 5-5 of Fig. 4;

Fig. 6 is a fragmentary plan sectional view taken generally on the line 6-6 of Fig. 4, and

Fig. 7 is a fragmentary plan view taken generally on the line 7-7 of Fig. 4.
15 In the embodiment of the invention in which I have chosen to illustrate the same, I have shown the lower flange 10 of a carburetor, and a housing 12 directly therebeneath and positioned between the carburetor 10 and the intake manifold 14.

The housing 12 is provided with a round conduit 16 adjacent its upper end which terminates in a square conduit 18 adjacent its lower end. A manually operable valve 20 is provided in the 25 conduit 16 positioned upon a shaft 22 which extends through the housing 12 in both directions. The valve shaft 22 may be journaled in suitable ball bearing mountings 24 and 26 in appropriate 30 bosses 28 and 30 formed on the housing 12. In order to prevent air from entering the conduit from the exterior of the housing, I provide the 35 comparatively thin washers 32 adjacent the openings 34 and 36 in the housing 12. A pair of coiled spring members 38 and 40 serve to position the 40 washer 32 around the shaft 22 and against the wall of the housing, thereby permitting practically no atmospheric air to enter the conduit 16 from this source. The shaft 22 may be provided at its right end (Fig. 4) with a lever 42 which 45 may be connected by the usual linkage to either a hand operated handle or a foot throttle of the usual type found in automobiles. The opposite end of shaft 22 has an arm 44 secured thereto by means of a screw member 46. The arm 44 carries a roller 48 at its lower end which is mounted for rotary movement upon a stud 50.

The governor valve 52 which is of the offset type, is positioned adjacent one of the side walls of the conduit 18 and is mounted upon a shaft 54, being secured thereto by suitable screw members 56. The shaft 54 may be journaled in suitable ball bearing members 56 and 58 mounted in bosses 60 and 62 on the housing 12. This shaft 55 may also be provided with the thin washer 32 and spring member 38 for preventing atmospheric air entering through the opening 63 in the housing 12. The left end of shaft 54 (Fig. 4) may carry an arm 64 rigidly secured thereto and adapted to extend upwardly therefrom. The arm 66 has a cam face 64a to permit the desired tension when the valves are practically closed.

The governor valve shaft 54 may also carry an arm 66, rigidly secured thereto and provided at its 65 extended end with a roller 68. The roller 68 is adapted to engage a cantilever spring member 70 which has its opposite end secured in a pivotally mounted block member 72. The block member 72 is adapted to be rotated about its pivot by means of a lug member 74 carried by a screw-threaded stud 76. The stud 76 may be connected with a lock member 78 which is capable of manipulation by a key to move the lug 74 back and forth upon the screw 76 to adjust the tension 70 upon the cantilever spring member 70. This construction 75 may be generally similar to that shown

and described in the patent to Addison C. Hoof, No. 1,966,722.

The housing 12 may be provided with a vertical wall 80 provided with a peripheral flange 82 to provide a seat for a sheet metal cover member 5 84. The cover member 84 may be held in position by suitable screw members 86 at various points as desired.

The operation of my improved device is as follows: Whenever it is desired to manually control 10 the flow of fuel to the internal combustion engine, the lever 42 attached to the carburetor valve is manipulated and the speed of the vehicle upon which the unit is applied is controlled by hand. It will be noted that as the throttle valve 20 is 15 moved to a closed position that the roller 48 which bears against the arm 64 on the governor valve shaft 54 rotates the same and moves the governor valve toward closed position at exactly the same speed. In other words, at such a partially 20 closed position of the throttle valve 20 the governor valve 52 has been manually likewise moved toward closed position. Assuming now that the vehicle is being driven at a governed speed with the throttle valve wide open and the governor 25 valve at a partially closed position, the arm 64 will have been moved away from the roller 48 by the suction on the governor valve 52. The governor valve will be at a partially closed position controlling the speed of the vehicle at the set 30 speed. Any attempt to close the throttle valve to a more nearly closed position than the governor valve, will result in failure, as the roller 48 will strike the arm 64 and move the governor valve to a more nearly closed position if such an 35 attempt is made. For this reason it can be seen that the manipulation of the throttle valve here-tofore possible with its resultant "cheating" is effectively eliminated.

While I have illustrated and described a specific embodiment of the invention, it will be apparent to those skilled in the art that changes and modifications may be made in the exact details shown, and I do not wish to limit myself in any particular; rather what I desire to secure and 45 protect by Letters Patent of the United States is:

1. In apparatus of the class described, the combination with a housing having a passageway therethrough, a manually controllable valve in said passageway, a shaft connected thereto, a suction controlled valve in said passageway below said first named valve, a shaft connected thereto, and means co-operating between said valves for moving said suction controlled valve toward a closed position as said manually controlled valve is closed, said means including an arm on said first valve shaft, a roller at the end of said arm and an arm on said second valve shaft engaging said roller and moved thereby.

2. In apparatus of the class described, the combination with a housing having a passageway therethrough, a manually controllable valve in said passageway, a shaft connected thereto, a suction controlled valve in said passageway below said first named valve, a shaft connected thereto, 65 means co-operating between said valves for moving said suction controlled valve toward a closed position as said manually controlled valve is closed, said means including an arm on said first valve shaft, a roller at the end of said arm, 70 an arm on said second valve shaft engaging said roller and moved thereby to a closed position, and spring means for urging said second valve to open position.

3. In apparatus of the class described, the com- 75

binaton with a housing having a passageway therethrough, a manually controllable valve in said passageway, a suction controlled valve in said passageway below said first named valve, 5 and means connected between said valves for moving said suction controlled valve toward a closed position as said manually controlled valve is closed, said means including cooperating arms on both of said valves, a roller mounted on the 10 end of one of said arms, and a cam surface formed on the end of said arms for engagement with the roller whereby one of the valves will be moved unequally to the movement of the other valve.

4. In apparatus of the class described, the combination with a housing having a passageway therethrough, a manually controllable valve in said passageway, a shaft connected thereto, a suction controlled valve in said passageway below said first named valve, a shaft connected thereto, 15 and means cooperating between said valves for moving said suction controlled valve toward a closed position as said manually controlled valve is closed, said means including an arm on said first valve shaft, a roller at the end of said arm, 20 and an arm on said second valve shaft engaging said roller and moved thereby, the arm on said second valve shaft having a cam surface whereby said second valve is moved a different distance than said first valve.

25 5. In apparatus of the class described, the com-

bination with a housing having a passageway therethrough, a manually controllable valve in said passageway, a shaft connected thereto, a suction controlled valve in said passageway beyond said first named valve, a shaft connected thereto, and means co-operating between said valves for moving said suction controlled valve toward a closed position as said manually controlled valve is closed, said means including an arm operatively connected to one shaft, a roller on said arm, and a second arm operatively connected with the other shaft and engageable by the roller.

6. In apparatus of the class described, the combination with a housing having a passageway therethrough, a manually controllable valve in said passageway, a suction controlled valve in said passageway below said first named valve, and means connected between said valves for moving said suction controlled valve toward a closed position as said manually controlled valve is closed, said means including cooperating arms operatively connected with both of said valves, one of said arms having a contact means adjacent the end thereof, and a cam surface formed adjacent the end of the other of said arms for engagement by the first contact means whereby one of the valves will be moved unequally with the movement of the other valve.

ADDISON C. HOOF. 30

CERTIFICATE OF CORRECTION.

Patent No. 2,202,423.

May 28, 1940.

ADDISON C. HOOF.

It is hereby certified that error appears in the printed specification of the above numbered patent requiring correction as follows: Page 3, first column, line 11, claim 3, before "said" insert --the other of--; and that the said Letters Patent should be read with this correction therein that the same may conform to the record of the case in the Patent Office.

Signed and sealed this 2nd day of July, A. D. 1940.

(Seal)

Henry Van Arsdale,
Acting Commissioner of Patents.
